CANTILEVER RACK

Donald Frazier, R.D. 1, Mendham Road, Far Hills, N.J.
Filed Dec. 9, 1964, Ser. No. 417,193
6 Claims. (Cl. 211—176)

This invention relates generally to cantilever racks, and specifically to front loading brackets for such racks, with locking retainers. It is an object of the invention to provide a cantilever rack which has the convenience of front loading brackets.

It is yet another object of the invention to provide a cantilever rack with rigid locking retainers.

A still further object of the invention is to provide a cantilever rack which is economical, by reason of the use of standard, mill-rolled beams which are relatively inexpensive.

Another object of the invention is to provide a cantilever rack which is extremely flexible in use, is fully adjustable to intermediate heights, may be single or double sided, is free standing, may be coupled in a series with other columns, is sturdy and safe because the cantilever arms are entirely free of accidental displacement yet are at all times readily adjustable.

These objects and advantages, as well as other objects and advantages may be attained by the rack shown by way of illustration of the inventive concept in the drawings in which:

FIGURE 1 is a view in perspective of a cantilever rack;

FIGURE 2 is a view in perspective of a portion of an H-beam column;

FIGURE 3 is a view in perspective of a cantilever arm;

FIGURE 4 is a top view of a portion of the cantilever arm;

FIGURE 5 is a view in perspective of a retainer;

FIGURE 6 is a top, partially sectioned view of a column, with a cantilever arm locked in place by the retainer;

FIGURE 7 is a partially sectioned view in perspective of a column, with a cantilever arm locked in place by a retainer.

Cantilever rack systems which are adjustable are often inconvenient, for they cannot be readily moved, the arms are not readily added as required, nor are they readily removable if not required; they are costly since they are made from specially fabricated parts, and are difficult to adjust. It has been found that cantilever arms may be provided for a rack system which can easily be front loaded (i.e. applied to an H-beam at any chosen point on the face without being hoisted to the top of the beam in order to be fitted into embracing relationship with the beam). Likewise, the described cantilever arm can be removed without being lifted over and off at the top. Yet such a cantilever arm can be quickly and easily attached to the H-beam without any danger of it slipping. The H-beams stand free in their own sturdy base and need no attachment to any wall surface to sustain them. They can be made to many desired different heights, with cross-bracing of various widths, and many cantilever arms may be applied. Cantilever arms may be added, subtracted, and readjusted to suit the requirements of the user. The positive positioning of the cantilever arms does not permit any loose attachment that might result in the arms assuming a position in which the outer end is below horizontal.

Referring now to the drawing in detail, the cantilever rack provides a base 11, which may be an H-beam of standard design. A vertical column 12 in the form of an H-beam is attached to the base 11. Likewise, this verti-

2

cal column 12 may be standard stock. The vertical column 12 is provided with a series of holes 13 in the web 14. These holes 13 are adjacent to the rear portion of the front face or front wall 15. A second series of holes 17 may be located in the web 14 adjacent to the rear portion of the rear face or rear wall 16. The vertical column 12 is braced by side plates 18 connecting the vertical column 12 and the base 11. The vertical columns 12, mounted on a base 11, are arranged in pairs (see FIG. 1) and secured together by spacer assemblies 19 attached to the columns 12. If the columns are to be used with both front and rear cantilever arms, the base 11 may be extended rearwardly to provide balance for the back load.

15 A bracket of special design is provided for the columns 12. In the figures, the bracket 20 is shown shorter than it actually would be in order that it may not obscure other details if drawn to scale. The bracket 20 has a generally U-shaped horizontal cross section with a front wall 21 which has an internal width (as shown in FIG. 6) which is wider than either of the faces 15, 16 of the H-beam. This extra width is necessary to enable the bracket 20 to be applied to the face 15 without hoisting it to the top of and sliding it down the face 15 of the column 12. The bracket 20 has rearwardly extending legs 22, 22 which embrace the column 12. The bracket 20 is provided with two generally vertical ribs 23, 25 on the inner aspect of the legs 22, 22. These ribs 23, 25 are positioned differently from each other. The first rib 23 is spaced away from the rear wall 24 of the bracket 20 a distance only sufficient to receive the end portion of the face 15 of the column 12. The second rib 25, however, is spaced away a sufficient distance to receive the opposite end portion of the face 15 and also to receive 25 a leg of a retainer 26 as shown in FIGURE 6.

30 The retainer or angle 26 has two legs; a front leg 27, and a rear leg 28. The retainer 26 has a number of elongated bolt slots 29 in the rear leg 28. When the front leg 27 is engaged with the second rib 25 at the back of the face 15, a bolt 30 is inserted through the holes 29, 13 (or 17) and a nut 31 is applied and tightened. The fillet (concaved junction) 32 is engaged by the convex juncture of the legs 27, 28 and the retainer is firmly secured to the web 14. The face 15 is firmly seized between the bracket 20 and the front leg 27. For further security, 35 a stop 33 is attached to the inner aspect of the leg 27, and is positioned to engage the bottom of the second rib 25 on the bracket 20. Since the rib 23 cannot pass the stop 33, the bracket 20 is both functionally held and is also supported at the chosen level. The cantilevered arm 34 (usually more elongated than shown) supports the material to be stored.

40 It is noted that the face 15 is rearwardly thicker immediately adjacent to the fillet 32, so that the retainer 26 will tend to engage only a portion of the back of the face 25 (see FIGURE 6) and will strongly engage the second rib 25.

45 A sturdy rack of stability, made of standard structural members is provided, at low cost, ease of assembly, and convenience of adjustment.

50 The foregoing description is intended merely to illustrate an embodiment of the invention, for many changes in the selection, construction and arrangement of the parts may be made within the scope of the appended claims without departing from the spirit of the invention.

55 What is claimed:

1. A cantilever rack comprising:
- (a) a base,
- (b) a vertical column on the base,
- (c) a front wall on the column,
- (d) a web extending perpendicularly from the rear of the front wall,

(e) a U-shaped bracket embracing the front wall,
 (f) a first rib on the inside of the bracket extending
 behind the front wall at one edge,

(g) a second rib on the inside of the bracket generally
 opposite the first rib,

(h) an L-shaped retainer attached at one end to the
 web and longitudinally engaged at the other end
 with the second rib,

(i) a generally horizontal arm on the front of the
 bracket.

2. A cantilever rack comprising:

(a) the device according to claim 1 and

(b) a stop on the retainer engaged in supporting re-
 lation with the bottom of a rib on the bracket.

3. A cantilever rack comprising:

(a) the device according to claim 1 and

(b) the U-shaped bracket dimensioned sufficiently wide
 to be fitted horizontally into embracing engagement
 with the column.

4. A cantilever rack comprising:

(a) the device according to claim 1 and

(b) a rear wall on the column attached to the end of
 the web opposite the front wall and generally parallel
 to the front wall,

(c) a bracket and retainer attached to the rear wall 25
 in accordance with the bracket and retainer attached
 to the front wall.

5. A cantilever rack comprising:

(a) the device according to claim 1 and

(b) a fillet at the juncture of the rear of front wall 30 and the web,

5
 10
 15
 20
 25
 30

(c) the retainer pivoting on the fillet to engage the
 second rib whereby the rear of the bracket is firmly
 seated on the front wall.

6. A cantilever rack comprising:

(a) a base,

(b) a vertical column,

(c) a generally flat front wall on the column,

(d) a perpendicular, longitudinal, medial web in the
 rear of the front wall,

(e) a U-shaped bracket embracing the front wall,

(f) ribs on the opposite inner sides of the U-shaped
 bracket,

(g) an L-shaped retainer attached to the web at one
 end,

(h) the other end of the retainer engaged with a rib
 on the bracket,

(i) the other rib on the bracket engaged with the back
 of the front wall,

(j) a horizontal arm attached to the bracket,

(k) a stop on the retainer engaged with the bottom
 on a rib on the bracket.
